JOURNAL BOX

William Blackmore, Cleveland Heights, Ohio, assignor to National Malleable and Steel Castings Company, Cleveland, Ohio, a corporation of Ohio

Application July 6, 1935, Serial No. 30,079

13 Claims. (Cl. 308—85)

This invention relates to improvements in journal boxes for railway rolling stock and more particularly to journal boxes carrying a lubricant in a well portion thereof and devices for confining the lubricant and supplying it effectively to a journal.

One object of my invention is to provide an improved oil conveying system whereby positive lubrication of the bearing surfaces is assured at all times.

A further feature of my invention is the provision of an assembly of parts whereby each part is maintained in correct position when in use and its correct location is insured in the course of assembly.

Further objects and advantages will be apparent from a detailed description of an embodiment of my invention illustrated in the drawings in which:

20 Figure 1 is a vertical, longitudinal section through a journal box with a journal therein.

Figure 1A is a plan view of the journal box lid.

Figure 2 is a vertical, transverse section on the line 2—2 of Figure 1.

25 Figure 3 is a plan view of the oil stripper.

Figure 4 is a vertical section through the oil stripper taken on line 4—4 of Figure 3.

Figure 5 is another vertical, transverse section through the journal box and journal taken on line 5—5 of Figure 1.

Figure 6 is a plan view of the brass or bearing member which rests on the journal.

Figure 7 is a vertical section taken on line 7—7 of Figure 8, and

35 Figure 8 is a vertical section, similar to Figure 1, of a portion of the construction but showing the journal box raised with respect to the journal, and the oil conveyor and brass out of their correct positions, thereby interfering with insertion of the wedge.

In the drawings there is shown a journal 10 rotatably mounted in a journal box 11. This journal box may be of standard dimensions and made as a separate unit or cast integral with a 45 side frame as is well understood in the art, and comprises a casing or main housing 12 provided with a well 13 adapted to hold a supply of lubricant. A plug 14 may be removed to replenish the supply of lubricant and is preferably at the right height in the casing to act as a gauge.

50 The journal enters the housing through an opening 15 in one end thereof. At the opposite end of the housing an opening furnishing access to the interior of the journal box is closed by a 55 suitable cover or lid 16 hinged about the pin 17.

The box is supported on the journal by means of the brass 18 and the wedge 19, the brass being preferably lined with suitable bearing metal such as babbitt 18'. An oil conveying member 20 is freely supported by the journal and confined over the top of said journal in the groove 21 formed in the babbitt 18' and the under side of the brass 18. This oil conveying member may be of any suitable type preferably, however, of a flexible nature, such as a chain or belt, and is 10 large enough in circumference so that the lower or freely hanging portion thereof will dip below the surface of the lubricant in the well 13. A chain of the type disclosed in my pending application Serial Number 620,682 may be used advantageously.

15 A circular opening 22 is formed in the brass, the lower portion of which registers with the groove 21. A substantially annular shelf 23 is formed about half way down the opening and is 20 adapted to limit the downward movement of an oil stripping member 24 during assembly.

25 This oil stripper is circular in cross section and preferably shaped somewhat like a bolt with a very short shank (Figs. 3 and 4). The circular head 25, in its normal position, will preferably remain spaced from the shelf 23 of the oiling cavity to provide a slight clearance allowing the shank to rest on the oil conveyor. This head is provided with a series of holes 26 extending from 30 the top of the head to the bottom thereof, and which may conveniently be connected by a circular groove 27 on the under side of said head. Vertical grooves 28 are formed in the bottom portion of the wall of the opening 22 in the brass, 35 as best seen in Figure 6, and these serve to divide the shelf 23 into two sections. Thus, when the conveyor 20 rotates with the journal, carrying oil up with it, the stripper 24, resting on said oil conveyor, removes or scrapes off the oil which 40 may then pass up through the grooves 28 and the holes 26 in the stripper directly, if they coincide with each other, or by way of the groove 27 if the vertical passages are offset from each other. The wedge 19 covers the opening 22 and 45 makes this cavity into a closed pocket.

50 A small reservoir is thus formed in the brass. During rotation of the journal and oil conveyor, oil is forced up into this cavity under pressure. At first the oil acting upon the under surface of 50 the head 25 may lift the oil stripper 24. As the reservoir above the stripper becomes filled, however, the pressure of the lubricant therein forces the oil stripper down onto the oil conveyor and it is apparent, of course, that as the speed of 55

rotation increases, the pressure above the oil stripper correspondingly increases. Positive removal of oil from the member 20 is thus afforded at all times, and the stripper 24 which functions like a piston is restrained in its vertical movements.

Also registering with the groove 21, there are provided substantially vertical openings 29, 29 extending through the brass and connecting with 10 grooves 30, 30 in the top thereof. These grooves, 15 extending rearwardly about half the length of the brass, form small reservoirs for the lubricant. Openings 31, 31 similar to the openings 29, 29 also connect with these grooves and also with 15 grooves 32, 32 in the lower or bearing side of the brass.

When the oil stripping member is held against the oil conveyor as described above, a pressure is built up on the lubricant carried by the conveyor 20 and this lubricant is forced up through one of the openings 29, depending upon the direction of rotation of the journal, into a connecting groove 30 and is then distributed to the journal and its attendant bearing surfaces by way of a groove 32. The operation of this system of oil distribution to the bearing surfaces just ahead of the high pressure bearing areas is more particularly described in Patent 2,024,204 issued to Albert O. Buckius and myself, and in my Patent 2,024,205, 30 both patents granted December 17, 1935.

A projection 33 is provided in the oil well preferably integral with and extending from the casing 12 in a horizontal direction and immediately above the lower portion of the oil conveyor. This guard member is adapted to prevent the traveling oil carrying member from wrapping around or sticking to the journal and thus interfering with the supply of lubricant thereto and possibly damaging the parts. This 35 guard may be shaped, if desired, to conform with the curve made by the oil conveyor in its normal passage although other shapes may be used to perform the same function. An upwardly projecting web 34 is preferably provided integral with 40 this guard member and the housing for a purpose 45 which is described below.

The lid 16 may be provided with an inwardly extending bifurcated flange or rib having arms 35a and 35b adapted to project into the journal 50 box toward the journal when the lid is closed, as may be seen in Fig. 1A. This lid is also preferably provided around its periphery with some suitable sealing means such as a gasket 36 to provide a tight joint when closed.

It sometimes happens during the use of rail-way rolling stock that the journal box will move upwardly some distance with respect to the journal therein if the car is violently jarred during coupling and the like. By my construction any 55 possibility of the parts becoming dislodged or disarranged with respect to each other and thereby ceasing to perform their proper function, is prevented. The rib 37, preferably also integral with the casing, prevents the wedge member 19 60 from sliding out of place during normal operation. If the journal box is raised, however, in the manner mentioned the wedge member might be thrown out through the opening between this rib 37 and the flange 38 on the journal itself. 65 Such a possibility is prevented when the cover 70 16 is closed since the projections 35a and 35b effectively closes this opening.

The rib 34 acts to some extent as a gauge. During the assembly of the journal box, the box 75 is usually jacked up or raised as shown in Figs. 7

and 8. It will be apparent that the extent to which the box may be raised is limited in my improved construction by the rib 34. If the oil conveying member 20 is in a position to correspond with the groove in the brass 18, so that the latter rests properly on the journal, there will be just about sufficient room to insert the wedge member 16. If, however, the oil conveying member is not in a correct position the forward end of the brass will be held in the elevated position 10 shown in Figure 11 and the wedge cannot then be inserted but will strike the end of the brass. Thus, a reliable means is provided for determining when the parts are in correct relation to each other during the assembling operation. The rib 15 34 in addition to aiding materially, in the way explained, in the assembling operations, is also very useful during the operation of my new journal box since relative movement between the journal box and journal is definitely limited without, however, hampering the normally required freedom of the parts.

It will thus be seen that this construction is adapted to be very readily assembled, disassembled and repaired. Certain portions of the housing and lid are so designed that the parts cannot get out of place during operation and can not be improperly located in the course of assembly.

The terms and expressions which I have employed are used as terms of description and not 30 of limitation, and I have no intention, in the use of such terms and expressions, of excluding any equivalents of the features shown and described or portions thereof, but recognize that various 35 modifications are possible within the scope of the invention claimed.

What I claim is:

1. A journal box assembly including a housing having an oil well therein, a journal extending into said housing through one end thereof and normally movable vertically relative to said housing, an oil conveying member freely supported from said journal with its lower portion in said oil well, and an upwardly extending projection at the forward end of and integral with said housing below said journal, adapted to limit relative vertical movement between said housing and said journal.

2. A journal box assembly including a housing having an oil well therein, a journal extending 50 into said housing through one end thereof and normally movable vertically relative to said housing, an oil conveying member freely supported from said journal with its lower portion in said oil well, a guard member integral with said housing and overlying said lower portion of said oil conveying member and having an upwardly projecting web adapted to limit relative vertical movement between said housing and said journal.

3. In a journal box, a journal, brass and wedge members between said box and said journal, an oil conveying member carried by said journal, a groove in said brass arranged to receive said oil conveying member, an opening in said brass, the lower portion of which registers with said groove, 65 and an oil removing member in said opening, the walls of said opening being shaped to limit vertical movement of said last named member in one direction.

4. In a journal box, a journal, brass and wedge 70 members between said box and said journal, an oil conveying member carried by said journal, a groove in said brass arranged to receive said oil conveying member, an opening in said brass, the lower portion of which registers with said groove,

and an oil removing member in said opening, the walls of said opening being shaped to restrain downward vertical movement of said last named member, and said wedge covering the top of said opening to form a closed pocket.

5. In a journal box, a journal, brass and wedge members between said box and said journal, an oil conveying member carried by said journal, a groove in said brass arranged to receive said oil conveying member, an opening in said brass, the lower portion of which registers with said groove, and an oil removing member in said opening, said brass and said oil removing member having openings through which oil may pass to a point above 10 said member.

15. In a journal box, a journal, brass and wedge members between said box and said journal, an oil conveying member carried by said journal, a groove in said brass arranged to receive said oil conveying member, an opening in said brass, the lower portion of which registers with said groove, a member in said opening to remove oil from said oil conveying member, said wedge overlying said opening to form a closed pocket above said oil 20 removing member, and means for conducting oil from the oil conveyor to said pocket during rotation of said journal.

25. In a journal box, a journal, brass and wedge members between said box and said journal, an oil conveying member carried by said journal, a groove in said brass arranged to receive said oil conveying member, an opening in said brass, the lower portion of which registers with said groove, a member in said opening to remove oil from said oil conveying member, said wedge overlying said opening to form a closed pocket above said oil removing member, means for conducting oil from the oil conveyor to said pocket during rotation of said journal comprising grooves and 30 openings in the walls of the brass opening and said oil conveying member.

35. In a journal box, a journal, brass and wedge members between said box and said journal, an oil conveying member carried by said journal, a groove in said brass arranged to receive said oil conveying members, an opening in said brass, the lower portion of which registers with said groove, a member in said opening to remove oil from said oil conveying member, said wedge overlying said opening to form a closed pocket above said oil removing member, means including grooves in 40 the walls of said opening for conducting oil from

said oil conveying member to said pocket during rotation of the journal, and means to limit downward movement of said oil removing member during assembly.

45. A journal box comprising a housing adapted to receive a journal, brass, and wedge, means on said housing to prevent longitudinal displacement of the wedge, and a lid for said housing having an inwardly projecting member extending into the housing into horizontal overlapping relation 10 to said wedge and cooperating with said means for preventing displacement of the wedge when the lid is in closed position.

50. A journal box comprising a housing adapted to receive a journal, brass, and wedge, means on said housing to prevent longitudinal displacement of the wedge, a lid for said housing having an inwardly projecting member extending into overlapping relation to said wedge to cooperate with said means in preventing displacement of 20 the wedge when the lid is in closed position, and means in the lower portion of said housing limiting relative vertical movement between said housing and journal.

55. A journal box assembly comprising a housing, a journal therein, brass and wedge members supporting said housing on said journal means on said housing to prevent longitudinal displacement of said wedge, and a lid for said housing having an inwardly projecting member 30 adapted to limit downward movement of said wedge when the lid is in closed position.

60. A journal box assembly comprising a housing, a journal therein, brass and wedge members supporting said housing on said journal, means on said housing to prevent longitudinal displacement of said wedge, a lid for said housing having a member projecting into said housing beneath said wedge and cooperating with said means when the lid is in closed position to prevent displacement 40 of said wedge, and means in the lower portion of said housing to limit relative vertical movement between said housing and said journal.

65. In a journal box assembly, a housing, a journal therein, an oil conveying member on said journal, a brass having a groove arranged to receive said conveying member, a wedge adapted to be inserted in said housing above said brass, and means on said housing for preventing insertion of said wedge when said member is not properly received by said brass.

50. WILLIAM BLACKMORE.
